WILLIAM H. BROWN, OF SYRACUSE, NEW YORK, ASSIGNOR TO H. H. FRANKLIN MANUFACTURING COMPANY, OF SYRACUSE, NEW YORK, A CORPORATION OF NEW YORK.

CARRIAGE-OPERATING MECHANISM FOR RECORDING-MACHINES.

1,285,014.

Specification of Letters Patent. Patented Nov. 19, 1918.

Original application filed June 6, 1910, Serial No. 565,197. (Patent No. 1,212,320.) Divided and this application filed January 6, 1917. Serial No. 140,839.

To all whom it may concern.

Be it known that I, WILLIAM H. BROWN, a citizen of the United States, and a resident of Syracuse, in the county of Onondaga and State of New York, have invented a certain new and useful Carriage-Operating Mechanism for Recording-Machines, of which the following is a specification.

This invention relates to mechanism for actuating the carriages of machines as recording machines, and has for its object a particularly simple and efficient means for successively tensioning the spring and returning the carriage to its starting position. 15 The invention consists in the combinations and constructions hereinafter set forth and claimed.

In describing this invention, reference is had to the accompanying drawings in which 20 like characters designate corresponding parts in all the views.

Figures 1 and 2 are respectively a plan and a side elevation of a calculating machine embodying my invention.

Fig. 3 is a plan view of detached parts of the calculating machine.

Fig. 4 is an end elevation of the carriage actuating mechanism shown at the right of Fig. 3, the contiguous part of the frame of 30 the machine being shown in section.

Fig. 5 is a sectional view on line 5—5, Fig. 4.

I have here shown my invention as applied to the type of machine shown in my 35 Patent No. 1,212,320, granted Jan. 16, 1917, of which this application is a division.

This machine includes a carriage which is shiftable step by step in one direction as to the left, a spring normally under tension 40 for shifting the carriage in said direction, as to the left, an escapement for controlling the shifting movement, suitable means as keys for controlling the operation of the escapement, and means operating to return 45 the carriage to the right, this means operating to tension the spring and then return the carriage.

1 designates the carriage which includes an axially shiftable shaft 2 slidable in suitable bearings provided in standards or flanges 3 rising from the top plate 4 of the frame 5 of the machine. 6 designates a series of controlling wheels rotatably mounted on the shaft 2, and shiftable by the carriage

into denominational positions, as units, tens, 55 hundreds, etc. These wheels are provided with peripheral gear teeth. The carriage 1 also includes a support 7 carried by the shaft 2 and depending therefrom, and carrying a plurality of abutments 8 which coact with 60 the wheels 6 to limit them in numerical positions, as set forth in my pending application referred to.

The support 7 at its front end slides along the top plate 4 of the frame 5 and has a rack 65 9 with which coacts suitable escapement mechanism including alternately acting teeth 10, and 11, the tooth 10 being carried on an arm 12 mounted on a vertically extending rock shaft 13 suitably supported in 70 the frame 5.

The abutments 8 are operated by keys 14 which are suitably connected to rock shafts 15 having means thereon for operating the abutments 8. The keys all coact with a suitable universal bar which actuates the escapement shaft 13. 75

As the carriage 1 with the toothed wheels 6 thereon shifts laterally to the left, they are brought into position opposed to calculating 80 wheels mounted on a shaft 16 and are brought into mesh therewith in order to drive the same during the rotation of the shaft 2 by the operating member or handle to be hereinafter described, this rotation of 85 the shaft 2 also returning the abutments 8 to their starting position.

The shaft 16 carrying the calculating wheels, is mounted on carriage arms 17 which are movable forwardly by a spring 18 90 encircling a rod 19 and connected at one end to one carriage arm 17 and at its other end to a lug 20 depending from the top plate 4 of the machine. The carriage arms are controlled in their movement by the spring 18, 95 by the operating handle which rotates the shaft 2.

The mechanism thus far described forms no part of my invention, but constitutes the subject matter of my Patents Nos. 1,088,671, 100 Feb. 24, 1914, and 1,122,191, Dec. 22, 1914, Patent No. 1,212,320, granted Jan. 16, 1917, and the only part of said mechanism necessary to be considered in so far as the present invention is concerned, is a laterally shiftable carriage which is moved in one direction by a spring. 105

21 designates the spring which is connect-

ed to the carriage 1, or the support 7 thereof so that the carriage is shifted to the left by the spring when the escapement is operated and so that the carriage may be returned to the right independently of the spring and the spring tensioned independently of the movement of the carriage.

In the illustrated embodiment of my invention, the spring 21 is a coiled torsion spring arranged between two parallel arms 22 of a frame member or yoke 23 carried by the main frame 5 on the inner right hand side thereof, said spring encircling a shaft 24 journaled at its ends in the arms 22. One end of the spring 21 is fixed to a head 25 having a stop arm 26 coacting with the pin 27 projecting from the inner face of one of the frame arms 22, and the other end of the spring is fixed to a rocking head or driving member 28 and moves in reverse directions therewith, the rocking head 28 having an arm 29 which detachably engages one end of a lever or driven member 30 mounted between its ends on the contiguous end of the shaft 24. This arm 29 may also move into and out of engagement with the contiguous frame arm 22 in order to limit the movement, in one direction, of the rocking member 28 by the spring 21.

30 A link 31 connects the lever 30 directly to the carriage 1 or the support 7 thereof. The opposite end of the shaft 24 to that on which the lever 30 is mounted, is provided with an arm 32 thereon. The shaft 24 and the arms 30 and 32 rock as a unit.

The spring 21 as here shown, is tensioned by a plunger 33 guided in the frame 5 and movable vertically therein, and having its upper end projecting above the top plate 4 of the frame, the plunger being pivotally connected at its lower end by a pin-and-slot connection 34 to a rock arm 35 on the rocking head or driving member 28.

45 The shaft 24 is moved in the opposite direction to the movement thereof effected by the spring 21, and independently of the spring 21, by any suitable means as a plunger 36 guided in the frame 5 and extending vertically therein, and having its upper end projecting above the top plate 4 of the frame 5, the plunger 36 being pivotally connected at 37 at its lower end to the arm 32 mounted on the shaft 24. The plungers 33, 36 are arranged one in advance of the other in a direction lengthwise of the frame 5 and in the path of an operating member or handle 38 connected to the shaft 2, to rotate the same, and movable about the axis thereof, the plunger 33 being engaged by the operating member 38 before the plunger 36. This operating member 38 although connected to the shaft 2 is not mounted directly on said shaft in the illustrated form of my machine, but 60 is mounted upon the sleeve 39 encircling the

shaft 2 and connected to the shaft by a key 40 which works in a keyway 41 in the sleeve of greater width than the key.

Whether or not the operating member or handle 38 is mounted directly upon the shaft 70 2 or upon the sleeve 39 or upon any other part is immaterial in so far as this invention is concerned. The only feature to be considered in so far as the present invention is concerned, is that the plungers 33 and 38 75 are operated consecutively by any suitable means which happens to be a handle 38 operating other parts of the calculating machine.

Upon the operation of the escapement controlling the movement of the carriage 1 to the left, this operation being effected by the depression of any one of the keys 14, the spring 21 expands and actuates the rocking head 28, the lever 30, the link 31 and moves 85 the carriage 1 to the left. When the handle 38 is operated, the plunger 33 is depressed thus rocking the arm 35 of the rocking head 28 and compressing the spring 21 and moving the arm 29 of the rocking head 28 out 90 of engagement with the lever 30.

Consequently, when the plunger 36 is depressed, the shaft 24 is rocked by reason of the arm 32 to which the plunger 36 is connected, and the carriage 1 returned to the 95 right by reason of the rocking of the arm 30 and the link 31, bringing the lever 30 into engagement with the arm 29 of the rocking head 28 so that when the escapement is again operated, the carriage will be 100 acted upon by the spring 21.

What I claim is:

1. In combination, a carriage movable in reverse directions, a spring having a part thereof movable in one direction for advancing the carriage and movable in the reverse direction independently of the carriage, the carriage returning independently of said part of the spring, and means for moving said part of the spring independently of the 110 carriage and thereby tensioning the spring, substantially as and for the purpose described.

2. In combination, a carriage movable in reverse directions, a coiled spring, movable 115 means between the carriage and the spring for transmitting motion from the spring to advance the carriage and for permitting the spring when being tensioned to move independently of the carriage, and means for 120 tensioning the spring, substantially as and for the purpose specified.

3. In combination, a carriage movable in reverse directions, detachable engaging driving and driven parts, the driven part being 125 movable with the carriage, a spring for moving the driving part in one direction to actuate the driven part, said driving part being movable in the reverse direction independently of the driven part when the spring 130

is being tensioned, and means for tensioning the spring, substantially as and for the purpose set forth.

4. In combination, a spring movable in reverse directions, means for moving the carriage in one direction, said means including a rocking part movable in one direction for advancing the carriage and movable in the reverse direction independently of the carriage, the carriage returning independently of said rocking part, a spring for moving the rocking part in one direction to advance the carriage, and means for moving the rocking part in the reverse direction independently of the carriage to tension the spring, substantially as and for the purpose described.

5. In combination, a carriage movable in reverse directions, a coiled spring having a head connected to one end thereof and rocking in opposite directions, means between the carriage and the head detachably engaging the head, said means serving to transmit motion from the head to the carriage, and means for moving the head independently of the first-mentioned means and tensioning the spring, substantially as and for the purpose specified.

6. In combination, a carriage movable in reverse directions, detachably engaging driving and driven parts rocking about a common axis, the driven part being movable with the carriage, a spring for moving the driving part in one direction to actuate the driven part, said driving part being movable in the reverse direction independently of the driven part to tension the spring, and means for moving the driving part in said reverse direction, substantially as and for the purpose set forth.

7. In combination, a frame member, a carriage movable in reverse directions, driving and driven parts rocking about a common axis and arranged on opposite sides of the frame member, the driven part being movable with the carriage, and the driving part having an arm for detachably engaging the frame member and the driven part, a spring for moving the driving part in one direction to actuate the driven part, said driving part being movable in the reverse direction independently of the driven part to tension the spring, and means for moving the driving part in said reverse direction, substantially as and for the purpose described.

8. In combination, a carriage movable in reverse directions, a spring having a part thereof movable in one direction for advancing the carriage and movable in the reverse direction independently of the carriage, the carriage returning independently of said part of the spring, and a movable plunger connected to said part of the spring for moving the same independently of the carriage and thereby tensioning the spring,

substantially as and for the purpose specified.

9. In combination, a carriage movable in reverse directions, detachably engaging driving and driven parts rocking about a common axis, the driven part being movable with the carriage, a spring for moving the driving part in one direction to actuate the driven part, said driving part being movable in the reverse direction independently of the driven part to tension the spring, and a movable plunger pivotally connected to the driving part for moving the same in said reverse direction, substantially as and for the purpose set forth.

10. In combination, a carriage movable in reverse directions, a spring having a part thereof movable in one direction for advancing the carriage and movable in the reverse direction independently of the carriage, and means for moving said part of the spring independently of the carriage and thereby tensioning the spring and for moving the carriage independently of said part of the spring, substantially as and for the purpose described.

11. In combination, a carriage movable in reverse directions, a spring having a part thereof movable in one direction for advancing the carriage and movable in the reverse direction independently of the carriage, means for moving said part of the spring independently of the carriage, means for moving the carriage independently of the spring, and a single operating member for actuating both of said means, substantially as and for the purpose specified.

12. In combination, a carriage movable in reverse directions, detachably engaging driving and driven parts, the driven part being movable with the carriage, a spring for moving the driving part in one direction to actuate the driven part in said direction, the said driving part being movable in the reverse direction, independently of the driven part when the spring is being tensioned, means for tensioning the spring, and means for moving the driven part in the reverse direction, substantially as and for the purpose set forth.

13. In combination, a carriage movable in reverse directions, detachably engaging driving and driven parts rocking about a common axis, the driven part being connected to the carriage and movable therewith, a spring for moving the driving part in one direction to actuate the driven part in said direction, the driving part being movable in the reverse direction independently of the driven part to tension the spring, means for moving the driving part in said reverse direction, and means for moving the driven part in the reverse direction, substantially as and for the purpose described.

14. In combination, a carriage movable in

reverse directions, a rock shaft, detachably engaging driving and driven parts, the driving part being loose on the rock shaft, and the driven part being fixed to said shaft and connected to the carriage, a coiled spring encircling the rock shaft and connected to the driving part for moving the same, the driving part being movable independently of the driven part when the spring is being tensioned, and means for moving the shaft independently of the driving part, substantially as and for the purpose specified.

15. In combination, a carriage movable in reverse directions, detachably engaging driving and driven parts, the driven part being movable with the carriage, a spring for moving the driving part in one direction to actuate the driven part, the driving part having movement independently of the driven part when the spring is being tensioned, plungers connected, respectively, to the driving and driven parts, and an operat-

ing member for successively actuating the plungers, substantially as and for the purpose set forth.

25 16. In combination, a carriage movable in reverse directions, a rock shaft, detachably engaging driving and driven parts, the driving part being loose on the rock shaft and the driven part being fixed to said shaft and connected to the carriage, a coiled spring encircling the rock shaft and connected to the driving part for moving the same, the driving part being movable independently of the driven part to tension the spring, plungers 30 pivotally connected to the shaft and the driving part, and an operating member for successively actuating the plungers, substantially as and for the purpose described.

35 In testimony whereof, I have hereunto signed my name, at Syracuse, in the county of Onondaga, and State of New York, this 9th day of December, 1916.

40 WILLIAM H. BROWN.
